UNITED STATES PATENT OFFICE.

KEMP MODLIN, OF CLIO, SOUTH CAROLINA.

BROOM.

1,107,541.

Specification of Letters Patent. Patented Aug. 18, 1914.

Application filed September 2, 1913. Serial No. 787,767.

To all whom it may concern:

Be it known that I, KEMP MODLIN, a citizen of the United States, residing at Clio, in the county of Marlboro and State of 5 South Carolina, have invented certain new and useful Improvements in Brooms; and I do hereby declare the following to be a full, clear, and exact description of the invention, such as will enable others skilled in 10 the art to which it appertains to make and use the same.

This invention relates to brooms, and one of the principal objects thereof is to provide means for easily and quickly securing broom 15 material to a broom head.

Another object of the invention is to provide a broom which will be simple, durable, inexpensive to manufacture and capable of having any broom material easily secured 20 to the broom head and without the use of skilled labor or of tools.

With these and other objects in view, the invention consists in the construction, combination and arrangement of parts herein- 25 after more fully described and claimed, and illustrated in the accompanying drawings, in which like characters of reference indicate like parts throughout the several figures, and in which,

30 Figure 1 represents a top plan view of a broom constructed according to my invention, a portion of the handle being broken away, Fig. 2 represents a vertical longitudinal sectional view through a broom, and 35 Fig. 3 represents a vertical, transverse, sectional view of the broom.

Referring more particularly to the drawing, the broom head 5 comprises a semi-cylindrical strip of metal having an opening 40 centrally thereof and near one end, through which an eye-bolt 6 extends and having its opposite end provided centrally with a slot 7, through which the vertical portion 8 of a bent securing rod extends, the horizontal 45 portion 9 thereof having one end provided with an eye 10 to form a pivotal connection with the eye of the bolt 6. Bolt 6 and portion 8 of the securing rod both extend upwardly through broom head 5 and are 50 threaded on their upper ends for receiving thumb-nuts 11, whereby broom material 12 may be secured between the securing rod and the broom head, said material preferably being constructed of corn husks, but 55 it is to be understood that other material

may be used without departing from the spirit of the invention.

The diverging prongs 13 of a steel fork pass through spaced openings near the inner edge of head 5, and are secured thereto by 60 means of the inner and outer nuts 14 and 15 respectively, the body portion (not shown) of the fork being driven into the lower end of the handle 16 of the broom, said handle being provided with a malleable 65 metal ferrule 17 having an opening therein through which the body of the fork extends, into the end of the handle, so that a tight joint is secured.

Although I have shown eye-bolt 6 and 70 portion 8 of the securing rod as provided with thumb-nuts, if it is so desired, bolt 6 may be secured in position by means of an ordinary carriage nut. However, in either instance it is desirable to provide washers 18 75 between the securing nuts and the head of the broom.

Should it be desirable for any reason to remove the broom material and insert new material in its place, all that is necessary to 80 do is to remove thumb-nut 11 and swing the securing rod on its pivot 10, whereby the material may be disengaged and new material placed on the rod, the latter being secured in the manner already described. In 85 this connection it will be noted that slots 7 runs from one end of body 5 inwardly, to allow of rod 8 swinging upwardly. It will be noted that the nuts 14 on the inner side of body 5 are in direct contact with the 90 broom material, and that the latter is wedged into the body and against said nuts, and it will therefore become evident that material cannot be removed accidentally or intentionally by pulling one edge of the 95 same, so that nuts 14 serve the double purpose of securing the prongs 13 of the fork and of providing means for preventing the accidental removal of the broom material.

It will be noted that prongs 13 and handle 16 extend at an angle to the vertical longitudinal plane of the broom head, but the exact angle at which the handle projects from the head may be varied without departing from the spirit of the invention. The eye-bolt 6 and vertical portion 8 of the securing rod are positioned near the ends of body 5 so that the broom material may be embraced between said bolt and portion, so that said material may not be re- 100 105 110

moved from the broom by pulling laterally of the same.

Although I have described the preferred embodiment of my invention, I may desire 5 to make such changes in the construction, combination and arrangement of parts as do not depart from the spirit of the invention and the scope of the appended claim.

Having thus fully described my invention, 10 what I claim as new and desire to secure by Letters-Patent is,

A broom comprising a head, a securing rod pivotally connected with one end of said head and adapted to clamp broom material

against said head, a handle, a fork secured 15 therein and having its prongs diverging and secured to said head, nuts threaded on the ends of said prongs for securing the same to said head, means for clamping said material against said nuts.

In testimony whereof I have signed my 20 name to this specification in the presence of two subscribing witnesses.

KEMP MODLIN.
